(57) **CLAIM**

The ornamental design for a hand-held sharpener device, as shown.

DESCRIPTION

FIG. 1 is a perspective view of the hand-held sharpener device;

FIG. 2 is a right side elevational view of the hand-held sharpener device;

FIG. 3 is a right end elevational view of the hand-held sharpener device;

FIG. 4 is a left side elevational view of the hand-held sharpener device;

FIG. 5 is a left end elevational view of the hand-held sharpener device;

FIG. 6 is a top plan view of the hand-held sharpener device; and,

FIG. 7 is a bottom plan view of the hand-held sharpener device.

The broken line showing of FIG. 1 is for illustrative purposes only and forms no part of the claimed design.
